This invention relates to improvements in electrical sockets in or for electrical dry batteries.

Sockets for this purpose are commonly made of a sheet of electrically insulating material with the tubular part of each contact projecting through an aperture therein so as to extend away from one face thereof and a further sheet of electrically insulating material riveted to the other face of the first mentioned sheet and formed with apertures arranged to overlie the tubular part of each contact to permit access thereto. The main disadvantage of such known sockets is that the tubular part of each contact is unshielded and care must be taken that it does not undesirably contact an electrically conducting part when in use. This usually necessitates the provision of an electrically insulating shield or suitably spacing the socket from the conducting parts with which it is to be associated. The provision of a shield involves additional expense both in labor and material and spacing the socket from the associated conducting parts involves the use of additional space which is highly undesirable when a compact assembly is desirable as in the case, for example, of electric dry batteries.

It is an object of the present invention to provide an improved electric socket for an electrical dry battery which shall not be subject to the disadvantage referred to.

The present invention, broadly stated, provides in or for an electric dry battery assembly an electrical contact supporting element for an electrical socket, the said supporting element including a sheet of electrically insulating material, at least one electrically insulating sheath formed as an integral pocket in said electrically insulating material, the pocket opening into one face of the sheet, the pocket extending outwardly from the other face of the sheet and having a closed end, and each pocket being shaped to receive and locate a substantially tubular part of an electrical contact, whereby any tubular electrical contact supported in the supporting element is protected and insulated from other parts of the assembly.

Further objects in the invention are to provide an electrical socket comprising an improved electrical contact supporting element and to provide an improved electric dry battery in combination with the said electric socket.

Furthermore detailed objects of the invention will be apparent from the detailed description which follows.

One embodiment of the invention will now be described by way of example, reference being made to the accompanying drawings, in which:

FIGS. 1 and 2 are respectively top and underneath perspective views of an electrical contact-supporting element according to the invention,

FIG. 3 is a fragmentary top plan view of an electric dry battery embodying an electrical socket according to the invention,

FIG. 4 is a section taken on the line III—III of FIG. 3,

FIG. 5 is a section taken on the line IV—IV of FIG. 3,

FIG. 6 is a plan view of an insulating cover sheet,

FIG. 7 is an enlarged plan view of one electrical contact, and

FIG. 8 is an elevational view of the contact shown in FIG. 7.

In this example, an electric socket indicated generally

2

at 1 and intended to receive the substantially tubular pins of a two-pin plug is associated with an electric dry battery composed of four cells 2 connected in parallel, the electrical connections being shown in FIG. 3. Each cell is of known kind being composed of a substantially cylindrical casing 3 forming one electrode of one polarity and a centrally disposed second electrode 4 of opposite polarity, a packing of pasty material being disposed between the electrodes of each cell to provide the electrolyte. 10 Each cell is capped with an annular disc 5 of electrically insulating material surrounding the projecting part of the associated second electrode 4 and overlying the casing 3 to avoid any short-circuit occurring between the electrodes of the cell. The cells are arranged as illustrated so as to make a compact assembly capable of being received in a close fitting substantially square section carton (not shown). This leaves a substantially diamond section space centrally between the cells the larger part of which may, or may not, as desired, be filled with a light-weight packing material.

The electrical socket 1 comprises a substantially rectangular sheet 6 of electrically insulating material which, in this example, is polystyrene, a thermoplastic material. This sheet is formed with a shallow recess or depression 7 in one face thereof, the upper face as illustrated in the drawings, this recess 7 extending for the full length of the sheet. A narrow embossed channel 8 opening into the upper face of the sheet 6 is formed in the latter to extend parallel with and centrally of the recess 7, this channel 8 extending from the major part of the width of the sheet 6 but terminating short of the ends thereof. The channel 8, for the major part of its length, has a depth substantially equal to the length of the pins to be accommodated by the socket and forms a stiffening rib which extends from the underside of the sheet and which serves as a means for locating the socket in the above-mentioned diamond section space. Two pockets 9 are formed in the sheet 6 to open into the base of the recess 7 and into the channel 8, the pockets 9 being symmetrically disposed about the centre of length of the channel 8. Each pocket 9 is integral with sheet 6 and has a depth corresponding to that of the channel 8 and is substantially diamond-shaped in cross-section to accommodate the correspondingly shaped substantially tubular part 10 and 10' of an electrical contact in position in FIG. 3. Each tubular part 10 has an open side to permit it to expand and grip a slightly oversize pin inserted therein in known manner. As only a two-pin plug is to be accommodated in this example, the tubular parts 10 and 10' of the two electrical contacts are of different sizes of ensure that the correct pin is inserted into the corresponding tubular part 10. The pockets 9 are correspondingly dimensioned to receive the associated tubular part 10 as a slight push fit.

Each tubular part 10 of an electrical contact is provided with two claws 11 which engage the periphery of the associated pocket and is formed integrally with a lug or tag 12, 12' which extends away therefrom and to which an electrical connection may be made. The claws 11 and the lugs or tags 12, 12' are accommodated in the recess 7 so as not to protrude above the general plane of the upper face of the sheet 6.

The channels 13 are formed in the upper face of the sheet 6, one adjacent each end of the channel 8, the channels 13 extending normal to the channel and having a depth less than that of the channel 8 but greater than that of the recess 7. The channels 13 open at or adjacent to their ends into dimples 14 having a depth greater than the channels 13 and disposed one towards each corner of the sheet 6. The dimples 14 provides supporting projections 17 on the underside of the sheet 6 and bear one on each annular disc 5 to support the socket against pressure exerted thereon when the pins of a plug are inserted

therein. The channel 8, as mentioned above, and the channels 13 provide stiffening ribs on the underside of the sheet 6 although it will be appreciated that the thickness of the latter is sufficient for it to be self-supporting although some degree of resilient deformation can be tolerated.

A sheet 15 of the same material as the sheet 6 and of the same dimensions is secured to the upper face of the sheet 6 preferably by a solvent welding technique although when the material is a thermoplastic material a heated tool may be used for this purpose. If the material is a thermoplastic material having suitable proportions of polar ingredients, for example polyvinyl chloride-acetate copolymers, high frequency dielectric heating may be used. In this way it is ensured that the sheets 6 and 15 are united over a relatively large surface area to provide a stronger assembly than is normally achieved using rivets. The sheet 15 is provided with apertures 16 and 16' of different size arranged to overlie the pockets 9 to permit access to the parts 19 of the electrical contacts.

In use, the socket is arranged with the projections formed by the dimples 14 bearing on the annular discs 5 and the channel extending diagonally across and within the diamond-section space between the cells. Each tubular part 10 of an electrical contact is sheathed in the associated pocket 9 and so cannot make electrical contact with a part of the cells although it can be in very close proximity thereto. All four electrodes 4 are electrically connected together and to one lug or tag 12 and the four electrodes 3 are electrically connected together and to the other lug or tag 12'. The whole assembly is received as a close fit in a carton (not shown) which is formed with a cut-out portion intended to overlie the socket 1 and permit access to the tubular parts 10 of the electrical contacts. The whole assembly is robust and the socket 1 occupies the minimum of space and requires the minimum of components. The sheet 6 is preferably shaped by a vacuum forming technique and it will be appreciated that the socket is relatively inexpensive to produce and easy to assemble.

It will be understood that the invention is not limited to the provision of an electrical socket intended to accommodate a two-pin plug and that the socket may be constructed to accommodate any number of pins, for example four pins, a pocket being formed in the sheet 6 for each electrical contact intended to engage a pin. When pockets are provided for four pins there will be two channels 8 associated with respective pairs of pockets.

The socket 1 need not necessarily be arranged at the top of the cell assembly. It may be arranged at the side thereof with the projections 17 provided by the dimples 14 bearing on the cylindrical casing 3 of two adjacent cells and the channel 8 extending into the substantially triangular section space left between the two adjacent cells; if desired the width of the sheet 6 may be greater than that of the sheet 15, the ends of the tag 12

remaining exposed and accessible, and this width being selected to be such as to be substantially equal to the corresponding dimension of the carton in which the assembly is to be received so as to locate the socket 1 accurately in the carton with respect to the cut-out portion thereof.

In a modified embodiment of the invention the projections 17 provided by the dimples 14 may be omitted.

Further, the sheet 6 may be provided with a plurality 10 of pockets each to receive an electrical contact and a plurality of contact tag or lug-receiving recesses which extend away from the pockets in any desired direction.

I claim:

1. An electrical socket for use in an electric dry battery 15 assembly, comprising an electrically insulating base sheet integrally molded with at least two pockets opening into one face of the sheet and extending outwardly from the other face of the sheet, at least two electrical contacts 20 respectively located in the pockets, each contact including a spring metal grip which is a push fit in its pocket and is protected and insulated thereby from other parts of the assembly, and a connecting metal lug secured to said grip and extending over said one face of the sheet, and a further sheet of insulating material overlying said lugs 25 and secured to said one face of the base sheet and having apertures overlying the pockets to permit insertion of plug pins into the pockets to be engaged by said grips.
2. A socket according to claim 1, wherein each said spring metal grip is substantially tubular, and said one 30 face of the base sheet is formed with a recess extending from the opening of each pocket to an edge of the sheet, the connecting lug of each contact being located in one of said recesses and extending beyond an edge of the sheet.
3. A socket according to claim 2, wherein each pocket is shaped to snugly receive and enclose said substantially tubular grip of the contact associated therewith.
4. A socket according to claim 1, wherein the base 35 sheet is formed with a stiffening and locating rib extending from said other face of the sheet and connected to said pockets.
5. A socket according to claim 1, wherein said one face of the base sheet is provided with a plurality of dimples which project beyond the other face for supporting the 40 base sheet above a supporting surface.
